UNITED STATES PATENT OFFICE

2,691,951

THREAD GUIDE FOR SEWING MACHINES

Warren Hansen, East Moline, Ill., assignor to
 Gellman Manufacturing Co., Rock Island, Ill.,
 a corporation of Illinois

Application September 26, 1952, Serial No. 311,747

2 Claims. (Cl. 112—218)

1

This invention relates to certain new and useful improvements in thread guides for sewing machines especially, though not necessarily, of the domestic type.

The thread guide of a sewing machine is generally located on the needle chuck. Prior to the advent of my invention it was a laborious and costly job to firmly connect the thread guide to the chuck. This resulted in increased cost of manufacture of the sewing machine as well as an increase in the selling price thereof.

My invention has for its object the provision of a thread guide which by means of a simple operation is easily formed to provide a simplified means of attachment to the chuck of the needle bar which attachment can be quickly and easily accomplished with a minimum degree of labor.

Another object of the invention is to provide in a thread guide for a sewing machine a loop or eye of a construction and form such as will permit easy threading of the thread through the eye and which will function to prevent accidental unthreading of the thread from such eye.

Another and equally important object of my invention is the provision of a thread guide which may be readily detached from the needle chuck for replacement purposes and the like.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a fragmentary perspective view of a sewing machine illustrating my thread guide associated therewith;

Fig. 2 is a fragmentary side elevational view of the same;

Fig. 3 is a perspective view of the thread guide embodied in my invention; and

Fig. 4 is a sectional detail view of the needle chuck with which my thread guide is associated.

For a better understanding of my invention, the size of the various parts illustrated in the drawings is somewhat exaggerated. The conventional sewing machine includes a head 10 from which depends a bushing 11 through which a needle bar 12 is reciprocated. This needle bar carries a chuck 13 into which the shank of a needle 14 is removably fixed by a thumb-screw 15.

In carrying my invention into effect, I provide in a wall 16 of the chuck 13 a threaded opening 17 into which my improved thread guide is threaded.

Such guide comprises a single length of spring wire formed to provide at one end portion a coil 18 consisting of a plurality of convolutions 19. The outer convolution 20 of the coil 18 terminates into an open eyelet 21 which extends laterally and transversely of the coil. It is through this eyelet 21 that the thread 22 passes on its way through the eye 23 of the needle 14. The open portion 24 of this eyelet 21 is preferably located within the confines of the convolution 20 so as to prevent accidental unthreading of the thread from the eyelet 21.

By simply threading the coil 18 into the opening 17 the thread guide is quickly and easily connected to the chuck 14. As the inner convolution of the coil bears against the shank 25 of the needle 14, continued rotation of the coil 18 in a clockwise direction, will cause the convolutions of the coil to wedge against the threads of the opening 17 thereby to firmly hold the thread guide against rotation during operation of the sewing machine.

From the foregoing, it is clear that I have provided a thread guide which is not only simple in construction and easy of manufacture but also one which, by a simple operation, may be firmly connected in position upon the chuck 13 of the needle bar with the least amount of labor; one which while firmly held in such position may be quickly and easily removed for any purpose.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A thread guide for a sewing machine comprising a single length of wire having one end formed to provide a hollow coil for threading into an opening of a needle supporting chuck, said member at one side of said coil having its oppo-

site end bent to provide an eye having an open end through which thread is threaded, said eye extending laterally from said coil and having its open end within the confines of said coil.

2. A thread guide for sewing machines comprising a single length of spring wire having hollow circular means providing for threaded connection with a needle supporting chuck, said length of wire opposite said means bent laterally and transversely with respect to said means to form an eyelet open at one end through which thread is threaded, the open end of said eyelet being confined within said means. 10
